UNITED STATES PATENT OFFICE.

JOHN HOPSON, JR., OF NEW LONDON, ASSIGNOR TO THE WATERBURY CLOCK COMPANY, OF WATERBURY, CONNECTICUT.

DESIGN FOR A CLOCK-CASE.

SPECIFICATION forming part of Design No. 23,723, dated October 23, 1894.

Application filed September 25, 1894. Serial No. 524,113. Term of patent 7 years.

To all whom it may concern:

Be it known that I, JOHN HOPSON, Jr., of New London, in the county of New London and State of Connecticut, have invented a new 5 Design for Clock-Cases, (Case D); and I do hereby declare the following, when taken in connection with the accompanying drawings and the letters of reference marked thereon, to be a full, clear, and exact description of the 10 same, and which said drawings constitute part of this specification, and represent, in—

Figure 1, a face view; Fig. 2, a side view.

This invention relates to a design for clock cases, and the design consists in the configuration and ornamentation as hereinafter described and shown in the accompanying illustrations.

The sides of the case consist of two inversely curved scrolls A, projecting beyond 20 the plane of its front. In the upper center is the dial-plate opening B, surmounted by an overhanging inverse scroll C, having a shell and scroll ornament D, within its embrace. The lower half of the opening B is surrounded 25 by a beading E, which merges into the scroll work above.

The lower part of the case is ornamented by a festoon of foliated work F, with waving ribbons G, floating down to near the bottom of the case, the lower outline of which is 30 formed by a series of connected scrolls H.

The sides of the case, which conform in outline to the projecting scrolls A, are ornamented by a broad foliated band I, set in a plain depressed pannel J, overlapped at the 35 top by a similar depressed panel and foliated band, also conforming in outline to the curve of the case, all as shown in the accompanying illustrations.

I claim—

40 The design for a clock-case as herein shown and described.

In testimony whereof I have signed this specification in the presence of two subscribing witnesses.

JOHN HOPSON, JR.
